DIE

Arvid C. Ericson, Toledo, Ohio, assignor to
Doebler Die-Casting Co., Toledo, Ohio, a corpora-
tion of New York

Application October 22, 1938, Serial No. 236,385

11 Claims. (Cl. 22—136)

This invention relates to dies for molding articles, and more especially to dies for metal die castings.

For good die castings, it is important to control factors such as the pressure of the molten metal, the temperature of the molten metal, the composition of the molten metal, and the temperature of the die. The first three factors have been controlled successfully, and the fourth has, therefore, become the most important factor at this time, and has heretofore presented great difficulty. The present invention constitutes an important improvement for control of die temperature.

A die should not be run cold because metal is prematurely chilled against the surface of the die and does not amalgamate perfectly with the remaining metal. This produces so-called "chill marks". The die is, therefore, preferably heated. It may, for example, be operated at a temperature of about 400° F. for a zinc base alloy, 550° F. for an aluminum base alloy, and 1000° F. for a brass base alloy. At the beginning of a working day, the operator of the die-casting machine usually heats the die with a torch in order to warm it up before beginning operation. I have so far considered the matter of overall temperature, but further difficulty results because the die may be overheated at some points, say, at a gate or slender core, yet may be too cool at other points, say, at the remote end of a long slender casting. To prevent overheating, water cooling has been used. This introduces many problems. It is difficult and expensive to make the necessary water connections, and in many cases, thirty or more connections must be made, each with appropriate fittings, and considerable lengths of flexible rubber hose, in order to afford movement of the die. The rubber hose soon dries or burns out because of the heat of the machine.

If water cooling is confined to the gate or overheated points, it is of no assistance in heating the remote or underheated points, and in fact may further cool the same. A really thin or slender core cannot be provided with water cooling because it is not enough to merely drill a hole in the core, but the hole must be large enough to receive a tube or a partition, for the water must circulate rapidly through the core if it is to be of any help.

The cooling effect of the water is regulated by appropriate valves. Often, separate valves are used on every water line for each of the cooling passages, in order to help approach, at least

to a slight extent, the desired temperature equalization in the die. Thus, some parts of the die may be fed with a slow water flow, and others with a fast water flow, depending upon examination of the castings being made, with skillful deduction concerning the parts that are overheated and the parts that are underheated, as manifested by defects of the casting. This matter is so important that the best machine operator is frequently the man who can best regulate the water valves.

However, the problem is more complex than has so far been indicated. Difficulty arises with the water supply itself, which frequently changes in pressure, thus resulting in changes in the speed of flow of the water. The water temperature itself changes from time to time. The temperature equilibrium depends on the rate of operation of the machine, for the primary source of heat is the molten metal being injected into the die. If the operator leaves the machine for only a few minutes, for some necessary purpose, the continued running of cold water excessively chills the gate or other cooled parts of the die, and the castings made after his return are defective until the die has again become heated up to normal temperature. The water might be shut down, but this is seldom done for a short stop because the operator dislikes to lose the relative adjustment of the valves which he has finally worked out in order to obtain good castings. Similar difficulty arises at noon time, though it is then more customary to shut the water off, but even in such case there is a waste of time and castings before bringing the die to optimum temperature. The temperature equilibrium, even if successfully worked out with water cooling, is critically related to the rate of casting, and applies to only one particular speed, say, one hundred shots an hour in one case, or two hundred shots an hour in another case, and so on. A change in the casting rate, as, for example, if the operator speeds up or slows down his operation of the machine, will upset the desired temperature balance.

It has already been mentioned that water cooling works only one way, that is, to cool the die. It cannot be used to heat up a cool part of the die. In order to heat up a cold spot, it is necessary to have overflow passages for the molten metal to flow into, which, of course, is wasteful of metal and troublesome in operation. Sometimes, an electric heater or a torch is kept continuously burning at the cold part of the die, thus presenting the double difficulty of making water

cooling connections at one part, and heating connections at another part of the die. In accordance with the present invention, both of these are eliminated, and the excess heat of an over-heated part of the die is transferred to and itself used to heat a cold part of the die.

Another and important disadvantage of water cooling remains to be mentioned. This arises out of the necessity for providing leak-proof passages for the water. Frequently, a cooling passage cannot be put where it is wanted and needed because it will cross or interfere with a reciprocable ejector pin or core pin, thus causing leakage of water. In a complex mold, there are sometimes a large number of ejector pins and core pins, and it becomes increasingly difficult to find clear space for the drilling of water passages. Even skilled die makers occasionally slip up and find that a water passage has intersected or contacted an ejector pin passage or the like, whereupon it becomes impossible to use water cooling in the die. The die must either be discarded, or, as is sometimes done, it may be operated without water cooling but at very slow speed, say, one-third the normal speed of production, until a new die can be made up. This same difficulty frequently occurs because a thin-walled part of a die, next to a water passage, may crack as a result of uneven expansion during use of the die. Such a crack causes water leakage and makes the die useless, except if used at very slow speed without water cooling.

In accordance with the present invention, the die is provided with inserts of a highly heat conductive metal such as copper. The inserts are usually in the form of round bars, but, as is later explained, in special cases may take other shapes and may even be flat plates or a combination of intersecting bars or intersecting bars and plates. The copper is disposed outside the mold cavity and does not come into direct surface contact with the molten metal. This is desirable to prevent the metal from alloying with the copper, for it has a much greater affinity to copper than to the steel die surface. The die thus remains all-steel surfaced, as is anyway desirable in order to prevent erosion by the molten metal. Excellent heat transfer between the die body and the inserts is desirable, and to this end, the inserts are preferably soldered to the die, thus making an excellent union for heat transfer, and preventing air film and possible oxidation of the surface of the copper.

Copper has ten times the heat conductivity of steel, which helps explain the benefit obtained with the present invention. In the case of a long slender casting, heat may be transferred from the gate to the cold remote ends of the casting by suitably disposed copper bars, and the die temperature is satisfactorily equalized without using overflow metal or heating devices at the cold spots. Cores are readily drilled and filled with a highly conductive insert. A core only one-eighth inch in diameter, for example, can be provided with a copper insert, although it would not be feasible to provide water cooling. Any metal having a high temperature coefficient of conduction may be used. Silver, for example is even better than copper, and while it would be expensive for large inserts, it would not be at all prohibitive for thin inserts in slender cores.

The present improvement minimizes and in some cases even eliminates water passages, water connections, rubber hose, and valves, and to appreciate this fact, it should be kept in mind that

in complex dies, a single die would often employ many hundreds of feet of rubber hose, and a large number of connections and fittings. To merely mount the die in the machine, or to remove the same from the machine, would consume much working time because of the necessity for making so many water connections. Even more important, however, is the extreme flexibility and freedom obtained in locating the inserts. They may cross ejector pins, core pins and the like, without difficulty. Simple, straight passages may be drilled through the die at desired points. With water cooling alone, I frequently encountered a hot spot in the die which was inaccessible to cooling water, so that the die had to be operated at reduced speed. I have as yet never encountered a hot spot which is inaccessible to the addition of a copper rod or strip for cooling the hot spot.

The invention is particularly good for castings which must have a perfect finish suitable for chrome plating, and without preliminary grinding, either because of the intricate shape of the casting, or because of highly competitive conditions in the manufacture of the item in question, making grinding prohibitive in expense. A common example of this situation is the numerous die castings on automobiles, which should be given a smooth, perfect finish directly from the die, and ready for chrome plating, without surface grinding.

The invention is also invaluable in connection with multiple cavity molds. Heretofore, it was seldom that the various cavities could all be brought to the same temperature. With my invention, pyrometers have been inserted at the various cavities, and equal temperatures have been obtained. If necessary, this may even be done by trial and error after building the die, and while making a few preliminary castings. Any hot spots or cold spots discovered by examination of the surface texture or condition of the castings are corrected by adding appropriate heat distributing inserts. The invention is also readily applied to old dies heretofore arranged for water cooling. I have beneficially changed over many such older dies, and the change may be made with ease because the passages for the copper inserts may be drilled through the die body (after first removing the ejector pins, core pins, etc.), without paying any attention to water passages and the holes for ejector pins and core pins. After the inserts have been secured in place, the holes for the ejector pins and core pins are re bored to cut through the copper at any points where the copper may have intersected these holes. The pins are then replaced.

To the accomplishment of the objects generally outlined above, and such other objects as will hereinafter appear, my invention consists in the die elements and temperature distributing and regulating elements, and their relation one to the other, as hereinafter are more particularly described by way of a number of specific illustrative examples showing a variety of ways in which the invention may be applied. The examples are illustrated by drawings, in which:

Fig. 1 shows the parting face of the cover half of a single cavity die embodying the heat distributing inserts of the present invention;

Fig. 2 is a plan view of the ejector half of the die;

Fig. 3 is a section taken in the plane of the line 3-3 of Fig. 2, with the die closed;

Fig. 4 is a plan view of the ejector half of a

75

multiple cavity die section intended to be used in a sectional die;

Fig. 5 is a side elevation of the cover half of the die of Fig. 4;

Fig. 6 is a partially sectioned side elevation of the ejector half of the die taken in the plane of the line 6—6 of Fig. 4;

Fig. 7 is a plan view of the ejector half of a section for a sectional die, utilizing intersecting transversely disposed inserts;

Fig. 8 is a plan view of the cover half of the die;

Fig. 9 is a section through the ejector half of the die taken in the plane of the line 9—9 of Fig. 7;

Fig. 10 is a section with the cover half of the die taken in the plane of the line 10—10 of Fig. 8;

Fig. 11 is a plan view of the ejector half of a die provided with diagonally disposed heat distributing inserts;

Fig. 12 is a section through the die in closed condition taken in the plane of the line 12—12 of Fig. 11;

Fig. 13 is a parting face view of the cover half of the die arranged to combine both water cooling and the heat distributing inserts of the present invention;

Fig. 14 is a section through the die in closed condition taken in the plane of the line 14—14 of Fig. 13; and

Fig. 15 is a partial showing of a transverse section taken through the same die in the plane of the line 15—15 of Fig. 13.

Referring first to Figs. 1, 2, and 3, the die comprises an ejector part 12 and a cover part 14. The casting being made is a comparatively slender, curved ornamental product. The die parting face is, therefore, curved and irregular, as is indicated at 18 in Fig. 3. Metal is supplied through the cover die in the usual manner, the cover die being provided with the approximately hemispherical recess 20 for the nozzle of the die-casting machine. The ejector half of the die is provided with a mating gate post the seat for which is indicated at 22 in Fig. 2. This is adapted to receive a gate post of the type described in greater detail in connection with Fig. 15. The metal flows from the gate passage to the die cavity by means of a passage or gate 24 clearly shown in Fig. 1.

In accordance with the present invention, the die temperature is equalized by copper inserts or bars. Specifically, the cover die is provided with copper bars 26 and 28. These are disposed at an angle, as shown in Fig. 3, in order to more closely approach the die cavity. In Fig. 1, it will be seen that inserts 26 and 28 are disposed between the gate passage 30 and the mold cavity 16. In this way, heat is transferred from the gate passage to the ends of the comparatively slender casting. This tends to equalize the temperature of the die. For further cooling of the die, the inserts 26 and 28 are preferably prolonged or extended outwardly, as is shown at 32 and 34, thus providing a substantial amount of radiation or air cooling. In the specific case here shown, the bars were extended about ten inches.

The ejector half 12 of the die is provided with inserts 36 and 38. These are disposed at an angle, as shown in Fig. 3, in order to conform to the curved shape of the mold cavity. The inserts are located directly beneath the mold cavity, as is clearly shown in Fig. 2. The ends

of inserts 36 and 38 may be extended to form heat radiating members 40 and 42. It is significant, and it should be noted, that ejector pin 44 passes directly through insert 36. The same applies to ejector pins 46 and 48, except that these pass through insert 38. Ejector pins 50 pass partially through insert 36. There is no need to avoid these ejector pins, nor to displace the inserts sidewardly, merely to avoid the ejector pins. Instead, the inserts are located in the best possible manner for purposes of heat distribution and temperature regulation. This situation is to be contrasted with that arising with water cooling, for the moment a water cooling passage intersects an ejector pin passage, the die is spoiled because of leakage of water around the ejector pin and into the mold cavity.

It will be understood by those skilled in the art that in the present case, the ejector pins, other than pin 44, are located outside the casting, there being a special web or overflow at each pin to help eject the casting. It will also be understood that the ejector half 12 of the die is mounted on a suitable mechanism for providing the desired movement of the ejector pins even though they are disposed at an angle. Inasmuch as the ejector half of the die may be increased in bulk because of its angular disposition, the die impression itself may be formed on a special hardened steel insert 52 which is inserted in the die body, as shown in Figs. 2 and 3. The copper inserts 36 and 38 pass through the part 52 as readily as they pass through the remainder of the die body.

A good fit between the copper and the die, and a clean surface contact therebetween, are essential for best results. The copper may be driven into the die with a snug or even a force fit. If desired, a shrink fit may be used, as by treating the copper in "Dry Ice" (solid carbon dioxide), or by heating the die before forcing the copper into the die. If desired, the copper bars may be made oversize and may be provided with slits, affording a springy fit of the copper in the die. Also, the copper bars may be soldered to the die, thus insuring a clean surface, but the fit of the copper within the die should, nevertheless, be kept close, say, with a few thousandth of an inch clearance at the most. I find that it is better not to permit the use of solder at all if it becomes merely an excuse for poor fit, the die maker tending to rely on the solder to fill up even large spaces, which must not be done. In fact, the die operating temperature is such that the solder may melt and run out or run to the end of a passage, thus leaving air spaces between the copper and the die. When soldering is used, the copper bars are, of course, cleaned and tinned, and the die passages are tinned, or a supply of solder is placed therein, following which the copper bars are inserted while hot. An advantage of solder is in eliminating air film and oxidation of the metal surface, which otherwise might reduce the desired heat transfer. In referring hereinafter to the use of solder, it will be understood, first, that its use is optional, and second, that it should not be substituted for a good fit, the latter being essential with or without solder.

Attention is now directed to Figs. 4 through 6 of the drawings. These show one section intended to be detachably inserted in a large sectional die, as will be understood by those skilled in the art. The ejector half 54 of the die is shown in Fig. 4, and the single section has mul-

multiple cavities therein, there being four cavities 56, 58, 60, and 62 for forming handles for automobile window regulators. Cavity 56 is supplied with metal through gate 64; cavities 58 and 60 through gate 66; and cavity 62 through gate 68. These gates are at the inner end of the die section for registry with the master gate extending lengthwise down the middle of the main die receiving a substantial number of die sections, such as that here shown. The die sections are slid into the master die with the gate ends foremost. When water cooling is provided, the water connections must all be disposed at the outer or left-hand end of the die section, as viewed in Fig. 4. Various complex passages would have to be formed by intersecting numerous drilled holes and then plugging the outer or exposed ends of these holes in an effort to form water circulating passages having inlet and outlet connections, all concentrated at one end of the die section. These passages could not be used to heat up the ends of the cavities remote from the gates, and, on the contrary, would cool the same. Moreover, comparatively slender retractable cores 70 and 72 are provided at the ends of each cavity, and it would be very difficult to provide satisfactory water cooling of these cores, first because they are small, and second, because they are reciprocably mounted for movement by means of a core plate schematically indicated at 74.

However, the problem of temperature regulation is easily handled by means of the present invention. Ejector die 54 is provided with three suitably disposed copper bars or inserts 76, 78, and 80. These transfer heat from the gate end to the remote or cool ends of the mold cavities. They further transfer heat to the die and cause it to act as a large heat radiating body. Moreover, the ends of the inserts may be projected beyond the die, as shown in the drawing, thus additionally radiating heat. The cover half 82 of the die section is similarly provided with a suitable number, preferably three, inserts, one of which is shown at 84 in Fig. 5. In Fig. 4, it will be seen that ejector pin 86 passes through insert 78, and that cores 88 and 90 pass through inserts 76 and 80 respectively, but this is of no disadvantage, and the inserts are located without consideration of the fact that ejector pins or cores may have to pass through the same.

Moreover, the cores themselves may be cooled by inserts of highly conductive metal. Specifically, core 70 is hollowed and provided with a copper insert 92, and core 72 is similarly cored with copper, as is indicated at 94. These copper inserts effectively remove the concentration of heat around the end or tip of the core, and effectively distribute it throughout the length of the core, and this provides adequate cooling for the core.

Another example of the invention is shown in Figs. 7 through 10 of the drawings. This also constitutes one section of a sectional die, and in the present case, the die is intended to mold an ornamental box cover. The ejector part 100 of the die is raised to form a fixed core 102 conforming to the inside of the box. The cover die 104 has a cavity 106 conforming to the exterior of the box. The parting face 108 is, of course, disposed at the edge of the box. Molten metal is fed to the die cavity through a gate 110 which, as is usual with sectional dies, terminates at the end of the section for registration with the main gate passages in the master die receiving the sections. The molded box cover is ejected by

means of side ejector pins 112 and end ejector pins 114 and 116. These ejector pins are half cut away, as shown, in order to provide a broad bearing surface against the comparatively thin edge of the molded box cover. The outer parts of the ejector pins are cylindrical, as is indicated in Fig. 9, but the inner ends are semi-cylindrical, as shown.

The core 102 is cooled by two massive copper inserts 118 and 120, which are disposed at right angles to the parting face of the die. In Fig. 9, it will be seen that the inner ends of these inserts come well into the core 102, and thus function to carry heat away from the core. Moreover, the ejector die 100 is provided with additional inserts 122 which extend longitudinally of the die and below the parting face thereof. These preferably converge slightly at the gate end of the die, and thus function to transfer heat from the gate toward the remote end of the die. This not only helps radiate, but also helps equalize the die temperature. Referring to Fig. 7, it should be observed that the inserts 122 are preferably so disposed that they contact with or partially intersect the sides of the inserts 118 and 120. This helps carry heat away from the core and helps maintain the entire die at a uniform temperature. Moreover, it helps transfer heat from insert 118, which is near the gate, to insert 120, which is relatively remote from the gate, thus helping keep the entire core at a uniform temperature.

In this case, the inserts are not only soldered to the die, but are soldered to one another, in order to insure an effective heat transfer union therebetween. The method of constructing the die is practically self-evident, it being merely necessary to insert some of the inserts before drilling the holes for the transversely related inserts, or, if all of the passages are preliminarily made, it is merely necessary to re bore some of the passages after putting into place the transversely related inserts.

The cover die 104 is also provided with transversely related inserts in order to effectively distribute heat over the entire area of the die. Specifically, there are transverse inserts 124 and 126 which are disposed beyond the ends of the die cavity. These inserts are crossed by longitudinal inserts 128, the inserts 128 being disposed outside the top of the die cavity. The inserts are all suitably tinned and soldered to one another and to the cover die. They function to transfer heat from the hotter or gate end of the die to the cooler or remote end of the die, thus equalizing the die temperature, and they also function to dissipate heat by making the entire die a heat-radiating body.

It will be noted that, in the present case, the inserts do not project outside the die. Such projections are used only if greater heat dissipation is needed. For example, in the sectional die of Figs. 4-6, the inserts were projected about eight inches beyond the die. This depends to a large extent on the speed of operation of the die and the character of the metal being cast. The necessity for further heat radiation is readily determined upon beginning operation of the die. In practice, long inserts may be initially provided, and the projecting ends may later be shortened or cut off altogether if it is found desirable to reduce the heat dissipation in order to bring the die temperature up to desired value. It will also be understood that additional passages may be bored, and additional inserts provided, if it is

found necessary to increase the heat radiation or to change the heat distribution in the die.

Still another example of the invention is shown in Figs. 11 and 12 of the drawings. In this case, the die is a complete die and is intended to mold an ornamental plate having a cored boss at the three end points 140. Fig. 12 is a section through the die in closed condition, there being a cover die 130 disposed over an ejector die 132. Fig. 11 shows the ejector die with its seat 134 and passage 136 for the gate post. The nozzle passage through the cover die 130 is schematically indicated in broken lines at 138.

The casting is ejected by ejector pins 142 disposed beneath the molded piece. An ejector pin 144 is disposed beneath the gate. Additional outside ejector pins 146 are employed, as is well understood in the art, these acting upon webs of overflow metal intentionally provided for that purpose. The extensions, and any excess flash or fin, may be all simultaneously trimmed off in a trimming die.

In the present case, each half of the die is provided with two long, diagonally disposed inserts 148. These inserts are disposed on opposite sides of the gate and extend to the remoter parts of the mold cavity, specifically, the ends 150 and 152. In this way, heat is transferred from the overheated or gate portion of the die to the cooler remote parts of the same. The die temperature is thus equalized, and the entire massive body of the die helps radiate and thereby dissipate heat. In the present case, no extensions of the inserts 148 beyond the ends of the die proved necessary. Before ending the discussion of this die, it may be pointed out that a substantial number of the ejector pins pass through the copper inserts, and that one of the cores passes through a copper insert. This will be evident on inspection of Fig. 11.

Attention is next directed to the die illustrated in Figs. 13 to 15 of the drawings. This die is intended to mold a steering wheel hub. In Fig. 14, it will be seen that there is a cover die 160 and an ejector die 162 fitting together on parting face 164. Fig. 13 is a parting face view of the cover die, and illustrates the gate passage 166. This passage, as well as the nozzle opening 168, are clearly shown in Fig. 15. The casting being made is a cup-shaped member with a cored hub and web-like spokes between the shell and hub. Passages 170 and 172 are provided for sidewardly movable plates which have to do with the forming of spoke openings for the steering wheel. It is sufficient for the present purposes to consider the same as sidewardly pulled cores.

The present die is illustrated as an example of how the copper inserts of the present invention may be combined with water cooling, if desired. The present die also illustrates the use of copper inserts in plate form instead of rod form. Specifically, cover die 160 is provided with a comparatively flat circular plate of copper 174, while ejector die 162 has the flat circular plate of copper 176. Short rods or inserts 178 are disposed in the cover die, there being six such rods, as is clearly shown in Figs. 13 and 14. The upper ends of these rods intersect and are received in plate 174. Rods 178 are preferably soldered to the die and to plate 174, all as was previously described.

Similarly, the ejector die 162 is provided with six copper rods or inserts 180 (Fig. 15). These are rotatably displaced, however, relative to the rods 178, in order to come between six ejector

pins 182 which are so positioned as to act on the weblike spokes of the casting. The sectional elevation of Fig. 15 is taken at right angles to Fig. 14, and consequently, the inserts 180 show up clearly in Fig. 15, while the ejector pins 182 show up clearly in Fig. 14. It will be understood that the lower ends of the six inserts 180 are received in copper plate 176, just as was previously described in connection with the cover die, and that the parts are all preferably soldered together to insure good heat transfer.

The core 184 of the cover die is here shown as water cooled. For this purpose, it is hollowed at 186 and provided with water inlet and discharge pipes 188 and 190 leading into the passage 186. The outer end of passage 186 is stoppered by a suitable plug 192, and the passage is preferably divided or partitioned by an inserted wall 194 to insure circulation of the water downwardly and then upwardly in passage 186.

Such water cooling is often desirable for a gate post or sprue post, but even that may, if desired, be copper cooled. The practice to be followed in such cases may be illustrated by the copper cooled gate post best shown in Fig. 15. Adequate cooling at this point is essential in order to insure solidification of the metal at the sprue so that it will be carried out of the cover die and along with the ejector die as a part of the casting. Referring to Fig. 15, the gate post 200 is formed at the upper end of a cylindrical enlargement 202. This is in accordance with standard practice, the enlargement 202 being received in a mating seat formed in the ejector die 162. The post 200 is hollowed as far as practicable and is provided with a comparatively thin wall, as is shown in the drawings. This wall may, for example, be one-eighth of an inch in thickness. The gate post is provided with a copper insert 204, the upper end 206 of which is preferably turned to accurately fit the hollow in the gate post. The parts are preferably soldered together, as was previously described. For additional cooling, the outer end 208 of insert 204 may be projected well beyond the die. This projection may be a matter of ten or twelve inches, if desired. No inconvenience is caused by extension of the insert in this fashion because the gate post is located on the ejector die, which is anyway mounted on a large die base having ejector plate and core plate mechanism. This gate post construction may be standardized in accordance with conventional practice, so that in making new dies, it is merely necessary to provide the necessary standardized seat for the gate post. Such a seat is shown at 22 in Fig. 2, and at 134 in Fig. 11.

In connection with this die, it will be seen that the inserts 178 and 180 tend to convey the heat outwardly from the parting face where the hot metal first enters. The plates 174 and 176 convey heat to the outermost parts of the casting and interconnect the rods so that heat is distributed from hotter rods near the gate to cooler rods remote from the gate. The rods in the cover die surround the outside of the molding cavity, and the rods in the ejector die are disposed within the shell and between the shell and hub of the casting. Together, the rods and plates form a cage of highly conductive metal which intimately surrounds all parts of the casting despite the intricate nature of the casting. The temperature of the die cavity is thus made uniform. The water cooling helps dissipate heat from the copper inserts of the cover die, and this

effect, if more cooling is wanted, may be carried much further by providing special water cooling passages for that purpose.

Reverting now to Fig. 13, I may point out the additional copper insert 210. This has been added to cool the gate passage. It is simply a round copper bar the inner end 212 of which is brought close to the gate, and preferably between the gate and the mold cavity, in order to help cool the gate passage leading into the mold cavity. The outer end of the insert is preferably extended beyond the die, as shown at 214. It will be clear that in this case, the sole function of the insert is to provide additional cooling of the gate passage.

It is believed that the present invention, and the method of applying the same to many conditions arising in molding practice, as well as the numerous advantages of the invention, will be apparent from the foregoing detailed description. It will also be apparent that while I have shown and described my invention in preferred forms, many changes and modifications may be made in the structures disclosed without departing from the spirit of the invention defined in the following claims.

I claim:

1. A die for die casting metal, ejector pins in said die, and means to redistribute heat in said die, said means consisting of elongated cylindrical rods made of a highly heat conductive metal, the die being bored with cylindrical holes which are disposed inside the die and close to but outside the die cavity, the rods being forced into said holes to fill the same, and one or more of said ejector pins passing slidably through the rods at points of intersection located inside the die body.

2. A die for die casting metal, core pins in said die body, and means to redistribute heat in said die, said means consisting of elongated cylindrical rods made of a highly heat conductive metal, the die being bored with cylindrical holes which are disposed inside the die and close to but outside the die cavity, the rods being forced into said holes to fill the same, one or more of said core pins passing slidably through the aforesaid rods at points of intersection located inside the die body.

3. A die for die casting metal, the body of said die being made of steel, core pins and ejector pins in said die body, and means to redistribute heat in said die, said means consisting of elongated cylindrical copper rods, the die being bored with cylindrical holes which are disposed inside the die and close to but outside the die cavity, at least a substantial part of the length of the copper rods being forced into said holes to fill the holes, said rods being soldered to the die in order to insure excellent heat conductivity therebetween, and one or more of said pins passing slidably through the aforesaid rods at points of intersection located inside the die body.

4. A die for rapidly repeated pressure casting, said die having solid metal parts of generally conventional configuration and separable on a parting face to open a die cavity formed inside said die, said cavity being small relative to the die parts, thereby leaving a substantial body of metal around the die cavity, and means to redistribute heat in said die, said means consisting of elongated cylindrical rods made of a metal having high heat conductivity, the solid metal of the die being bored with cylindrical holes which are disposed wholly inside the solid metal of the die and

close to but outside the die cavity, the rods being forced into said holes to fill the same with a tight fit, the metal of the die surrounding the metal of the rod all around the periphery of the rod.

5. A die for rapidly repeated pressure casting, said die having solid steel parts of generally conventional configuration and separable on a parting face to open a die cavity formed inside said die, said cavity being small relative to the die parts, thereby leaving a substantial body of steel around the die cavity, and means to redistribute heat in said die, said means consisting of elongated cylindrical solid copper rods, the solid metal of the die being bored with cylindrical holes which are disposed wholly inside the solid metal of the die and close to but outside the die cavity, the copper rods being inserted in said holes to fill the same and being soldered to the die in order to insure excellent heat conductivity therebetween, the metal of the die surrounding the copper rod all around the periphery of the rod.

6. A die for rapidly repeated pressure casting, said die having solid metal parts of generally conventional configuration and separable on a parting face to open a die cavity formed in said die, said cavity being small relative to the die parts and thereby leaving a substantial body of solid metal around the die cavity, and heat distribution means to cool a part of the die cavity which is apt to become overheated, and to simultaneously heat a part of the die cavity which would otherwise be too cool, by transferring heat thereto from the overheated part of the die, said heat distribution means including an elongated cylindrical insert of highly heat conductive metal, said insert being located with a tight fit in a cylindrical hole disposed within the solid metal of the die body and outside the die cavity but inside the outer walls of the die and so located that a part of the insert is disposed near the overheated part of the mold cavity and another part of the insert is disposed near the cool part of the mold cavity.

7. A die for rapidly repeated pressure casting, said die having steel parts of generally conventional configuration and separable on a parting face to open a relatively long die cavity and a tapered gate passage formed in and passing through the solid metal of said die, said cavity and gate passage being small relative to the die parts and thereby leaving a substantial body of steel around the die cavity and gate passage, and heat distribution means to cool the gate passage which is apt otherwise to become overheated, and to simultaneously heat the remote end of the cavity which would otherwise be too cool, by transferring heat thereto from the gate passage, said heat distribution means including a tightly fitting insert of solid copper, said insert being located within the solid steel of the die body and outside the die cavity but inside the outer walls of the die and being so located that a part of the insert is disposed near the gate passage and another part of the insert is disposed near the remote end of the mold cavity.

8. A die for rapidly repeated pressure casting, said die having solid metal parts of generally conventional configuration and separable on a parting face to open a die cavity formed inside said die, said cavity being small relative to the die parts, thereby leaving a substantial body of metal around the die cavity, a water cooling passage in said die, water cooling connections to said passage to cool the die, and additional heat distribution means to relatively cool a part of the die which is apt to become overheated despite

the aforesaid water cooling, and to simultaneously heat a part of the die which would otherwise be too cool, said heat distribution means including an insert of highly conductive metal so located in the solid metal of the die body that a part of the insert is disposed near the overheated part of the mold, and another part of the insert is disposed near the cool part of the mold, whereby the water cooling functions to remove heat from the mold at a desired rate in order to maintain the mold at a desired average temperature, while the insert functions to redistribute heat in the mold in order to maintain the individual parts of the mold at a desired relative temperature.

9. A die for rapidly repeated pressure casting, said die having solid metal parts of generally conventional configuration and separable on a parting face to open a die cavity formed inside said die, said cavity being small relative to the die parts, thereby leaving a substantial body of metal around the die cavity, and means to redistribute heat in said die and to cool the same, said means consisting of elongated cylindrical rods made of a metal having high heat conductivity, the solid metal of the die being bored with cylindrical holes which are disposed wholly inside the die and close to but outside the die cavity, said holes opening onto an outside wall of the die, at least a substantial part of the length of the rods being forced into said holes to fill the same with a tight fit, the metal of the die surrounding the metal of the rod all around the periphery of the rod, the outer ends of said rods projecting well out of the die body for added heat radiation.

10. A die for rapidly repeated pressure casting, said die having solid metal parts of generally conventional configuration and separable on a parting face to open a relatively long die cavity and a tapered gate passage formed in and passing through the solid metal of said die, said cavity and gate passage being small relative to

the die parts and thereby leaving a substantial body of metal around the die cavity and gate passage, and heat distribution means to cool the gate passage which is apt to otherwise become overheated, and to simultaneously heat the remote end of the cavity which would otherwise be too cool, by transferring heat thereto from the gate passage, said heat distribution means including an elongated cylindrical insert of highly heat conductive metal, said insert being received with a tight fit in a cylindrical hole disposed within the solid metal of the die body and outside the die cavity but inside the outer walls of the die and being so located that a part of the insert is disposed near the gate passage and another part of the insert is disposed near the remote end of the mold cavity.

11. A die for rapidly repeated pressure casting, said die having solid metal parts of generally conventional configuration and separable on a parting face to open a die cavity formed inside said die, said cavity being small relative to the die parts, thereby leaving a substantial body of metal around the die cavity, a water-cooling passage in said die, water-cooling connections to said passage to cool the die, and additional heat distribution means to redistribute heat in the mold, said heat distribution means consisting of one or more elongated cylindrical rods made of a metal having high conductivity, the solid metal of the die being bored with one or more cylindrical holes which are disposed in the solid metal of the die and close to but outside the die cavity, and the rods being received in said holes with a tight fit, the water-cooling functioning to remove heat from the mold at a desired rate in order to maintain the mold at a desired average temperature, while the heat distribution means or insert functions to redistribute heat in the mold in order to maintain individual parts of the mold at a desired relative temperature.

ARVID C. ERICSON.
